DRAIN FITTING AND METHOD OF PRODUCTION THEREOF

Adolph C. Recker, Watertown, Conn., assignor to
Chase Brass & Copper Co., Incorporated, Wa-
terbury, Conn., a corporation

Application August 27, 1938, Serial No. 227,156

5 Claims. (Cl. 29—157)

This invention relates to an improved construction and method of making drain-fittings having a strainer arranged transversely to the waterway extending therethrough.

The primary object of the present invention is to provide an improved construction and method of making a drain-fitting of this character whereby the period of time required to empty a lavatory bowl or similar receptacle may be reduced to a minimum.

Another object of the invention is to provide an improved construction and method of making a drain-fitting whereby quantity production of superior drain-fittings may be economically carried on.

One of the specific objects of the invention is to provide an improved drain-fitting having an integrally-formed water-way strainer; which may be advantageously constructed of drawn-tubular non-ferrous metals such, for example, as copper or copper-base alloys which are readily cold-worked to the desired form and provide smooth continuous surfaces for the inner walls of the drain-fittings whereby the resistance opposed to the outlet discharge of drainwater or other fluid is reduced to a minimum.

With the above and other objects in view, as will appear to those skilled in the art from the present disclosure, this invention includes all features in the said disclosure which are novel over the prior art.

In the accompanying drawing, in which certain modes of carrying out the present invention are shown for illustrative purposes:

Fig. 1 is a view in central-vertical section of a drain-fitting embodying the present invention, and shown as being placed in a lavatory-bowl or like receptacle;

Fig. 2 is a view on a smaller scale and in side-elevation of the drain-fitting shown in Fig. 1;

Fig. 3 is a similar view but viewing the drain-fitting from a right angle as compared to the showing of Fig. 2;

Fig. 4 is a top-plan view of the drain fitting;

Fig. 5 is a transverse-sectional view taken on the line 5—5 of Fig. 3;

Fig. 6 is a diagrammatic view in side elevation of the partly-completed drain-fitting, showing relative arrangement of piercings to be made and wall-portions to be operated upon; and

Fig. 7 is a view in side-elevation similar to Fig. 3, but showing a modified form of the drain-fitting embodying the present invention.

According to the embodied form of the invention shown in Figs. 1 to 6 inclusive, the drain-

fitting which is generally designated by the reference character 10, comprises: a tubular body-portion 11 provided with overflow-openings 12—12 and a bevelled-top-flange 13. The said overflow-openings 12—12 are oppositely arranged, each with respect to the other, and in vertical-register with an overflow channel 14 which extends upwardly around and conforms to the vertical curvature of the bottom wall 15 of a lavatory bowl as illustrated in Fig. 1.

The top-flange 13 of the drain-fitting 10 is suitably formed and arranged to be seated within a depression 16 formed in the bottom wall 15 of the lavatory bowl around an outlet-opening 17 therein which opens downwardly into a circular-overflow chamber 18 into which the overflow channel 14 discharges. The annular overflow-chamber 18 is formed within a protuberant-hollow-wall-portion 19 of the bottom wall 15 of the lavatory bowl. At the bottom, the said protuberant-hollow-wall portion 19 is provided with a tubular-neck 20 through which extends a circular-opening 21 coaxially aligned with the discharge-outlet-opening 17 in the bottom wall 15 of the lavatory bowl.

Throughout the greater portion of its length below the circular chamber 18, the tubular body-portion 11 is provided exteriorly with screw-threads 22 by means of which a clamping-nut 23 may be moved into clamping engagement with a gasket 24 interposed between the said clamping-nut 23 and the annular lower end of the tubular-neck 20. In this manner, the drain-fitting 10 is securely fastened to the bottom wall 15 of the lavatory bowl by the clamping-action of top-flange 13 and the clamping-nut 23.

As shown particularly well in Fig. 1, the drain-fitting 10 is provided with a waterway or flowage-channel 25 extending therethrough from top to bottom. Arranged transversely with respect to this waterway 25, is a strainer generally designated by the reference character 26 and comprising two strainer-members 27—27 which are formed by inwardly-displaced circumferential-portions of the tubular body-portion 11 of the drain-fitting 10. For this purpose and during the operation of forming the over-flow-openings 12—12 the tubular body-portion 11, in its original imperforate condition, may be operated upon by suitable cutting and forming dies to partially sever therefrom the circumferential wall-portions thereof which are subsequently displaced to form the strainer members 27 as well as to completely sever other wall-portions which, when removed, 55

provide the major-portions of the overflow-openings 12-12.

As shown diagrammatically in Fig. 6, during the progress of the piercing operation by which the overflow-openings 12-12 are formed, each of the said over-flow-openings may be formed in complementary portions in the following manner. According to the illustrated form of the invention shown in Figs. 1 to 6 inclusive, a circumferential wall-portion 28 (Fig. 6) of the originally-imperforate tubular body-portion 11 at the top, may be completely severed therefrom by piercing the wall of the tubular body-portion in parallel horizontal lines 29 and 30 and vertical lines 31 and 32 to form a portion of a given one of the overflow-openings 12-12 extending above the upper marginal edge of each of the strainer-members 27-27 to the top of said opening. At the same time, an additional circumferential wall-portion of the originally-imperforate tubular body-portion 11, corresponding to one of the strainer-members 27, may be partially severed therefrom by an additional piercing of the tubular wall along a horizontal line 33 substantially parallel to the circular line 30 already referred to. The circumferential wall-portion 27a, thus partially severed from the tubular body 11 merges with the circumferential wall of the said tubular body 11 but, in the course of the operations performed thereon, is displaced inwardly about halfway across the waterway 25 preferably to form one of the strainer-members 27. The wall-portion 27a is displaced into abutment with the oppositely-arranged wall-portion 27a so that the resulting strainer-members 27-27a meet adjacent the central-longitudinal axis of the said waterway 25.

According to the modified form of the invention shown in Fig. 7, a drain-fitting which is generally designated by the reference character 36, is constructed to comprise a tubular body-portion 37 which is provided at the top with a beveled top-flange 38 to be seated in the depression 16 of the bottom-wall 15 of a lavatory bowl.

According to this form of the invention, the major portion of each overflow-opening 39 is formed by the complete removal of a portion of the cylindrical wall of the tubular body-portion 37, immediately below the strainer which is generally designated by the reference character 40 and comprises two strainer-members substantially similar in construction and arrangement to the strainer-members 27-27 of the embodiment described above. Accordingly, the strainer 40 is formed by the inward displacement of the intermediate portions of partially-severed cylindrical wall-portions of the tubular body-portion 37, immediately above the major portion of a given overflow-opening 39 which is thereby increased in vertical dimension to an extent corresponding to the vertical depth of the strainer 40.

In making either of the illustrated forms of the invention, it will be seen that the tubular body-portion 11 (or 37) is made of suitable length in relation to its diameter to cause a free expansion of the issuing fluid column into flowing adherence with the inner wall of the drain-fitting below the "vena contracta" of the fluid column. At the same time, the overflow-outlets 12-12 (or 39) are conveniently arranged to break the vacuum which, in their absence, would occur around the "vena contracta" to exert a retarding influence on the outflow of the fluid column from the lavatory bowl or other receptacle.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A drain-fitting, comprising: a tubular body provided with an axial through-way for fluid and having oppositely-arranged overflow-openings in the circumferential wall of the said tubular body, the upper marginal portion of each of the said oppositely-arranged openings being formed by a partially-severed circumferential portion of the tubular body wall; the partially-severed portions each having a horizontal-extension and a vertical-extension and provided with a bottom wall and a top wall which merge with the tubular body wall at opposite ends, the said partially-severed portions of the tubular wall being each displaced inwardly into juxtaposition each with respect to the other to form complementary reentrant strainer-members in which the vertical-extension of each of the said partially-severed portions is presented in said through-way longitudinally thereof and its said top wall presents a surface of uniform size and of the width of the wall of the tubular body to fluid flowing through the said through-way.

2. A drain-fitting, comprising: a tubular body provided with a waterway extending axially therethrough and having oppositely-arranged overflow-openings in the circumferential wall thereof, each of the said overflow-openings being formed partly by the complete removal of a circumferentially-extending original wall-portion of the said tubular body and partly by a reentrant partly-severed circumferentially-extending wall-portion of the said tubular body, the said reentrant partly-severed circumferentially-extending wall-portions each having a horizontal-extension and a vertical-extension and provided with a bottom wall and a top wall and being merged circumferentially at opposite ends with the said tubular body and having their reentrant portions in juxtaposition, each to the other, to provide a strainer in which the vertical-extension of each of the said partly-severed portions is presented in said waterway longitudinally thereof and its said top wall presents a surface of uniform size and of the width of the wall of the tubular body, to fluid flowing through the waterway of the said tubular body.

3. A method of making a drain-fitting provided with a water-way-strainer, consisting in: forming a tubular body having a waterway extending therethrough; in forming an opening in the lateral wall of said tubular body by completely removing a circumferential wall-portion thereof; in partially-severing from the said tubular body adjacent the said opening, an additional circumferential wall-portion to provide a partially-severed portion having a horizontal-extension and a vertical-extension and provided with a bottom wall and a top wall and merging endwise with the tubular body-wall; and inwardly displacing the said additional circumferential wall-portion to provide a re-entrant portion located adjacent said opening and extending, at least, partway across the said waterway to form a strainer-member in which the vertical-extension of the said partially-severed portion is presented in said waterway longitudinally thereof, and its said top wall pre-

sents a surface of uniform size and of the width of the wall of the tubular body, to the flow of drainage water through the said waterway.

4. A method of making a drain-fitting provided with a waterway-strainer, consisting in: forming a tubular body having a waterway extending therethrough; completely removing oppositely-arranged circumferential wall-portions of said tubular body having their upper and lower marginal edges arranged in spaced horizontal planes transverse to the axis of the said waterway to form portions of oppositely-arranged overflow-openings; partially severing from the tubular body along corresponding marginal edges of the part-openings thus formed, additional circumferential wall-portions; the partially-severed additional circumferential wall-portions each having a horizontal-extension and a vertical-extension and being each provided with a bottom wall and a top wall; and inwardly-displacing the said additional circumferential wall-portions of the tubular body in a common transverse plane to complete the said overflow-openings and to form a strainer comprising the said inwardly-displaced additional circumferential wall-portions of the tubular body and each having the said vertical-extension thereof presented in the said waterway longitudi-

nally thereof and having its said top wall presenting a surface of uniform size and of the width of the wall of the tubular body, to fluid passing through the said waterway.

5. A drain-fitting, comprising: a tubular body provided with an axial through-way for fluids and having an opening in the circumferential wall thereof which is partly formed by the inward displacement into the said axial through-way, of a partially-severed circumferential portion of its tubular wall, the said circumferential portion of the tubular body wall having a horizontal-extension and a vertical-extension provided with a bottom wall and a top wall and its vertical-extension being of relatively small axial length in comparison with the axial depth of the said opening and having a reentrant medial bend formed therein and merging circumferentially in opposite directions with the said tubular body wall to form a strainer-member in which the vertical-extension of the said partially-severed circumferential portion is presented in said through-way longitudinally thereof and its said top wall presents a surface of uniform size and of the width of the wall of said tubular body to the flow of fluid through the said through-way.

ADOLPH C. RECKER.
